Whole No. 1407. Caleb W. Palmer, of Troy, N.Y.
Letter Patent No 42 dated May 7 1861.

The schedule referred to in these Letters Patent and making part of the same.

To all whom it may concern:

Be it known that I, Caleb W. Palmer, of the City of Troy, in the County of Rensselaer, and State of New York, have invented or produced a new and original ornamental Design for the Elevated Ovens of Baking Stoves; and I do hereby declare that the following is a full and exact description of the same, reference being had to the annexed photographic drawing, which makes a part of this Specification.

My ornamental design consists in the arrangement of the nearly open scroll, a, swelled or raised at the middle, b, and the border moulding, c, upon the door at the end of the oven; and the arrangement, upon the side plate of the oven, of the usual border moulding, d, the sunken panel with concave mouldings, e, for its sides, the tablet f, in its centre, and the corner and border ornaments, g, g, g, g, h, h, the whole framed or shaped and arranged as represented by the annexed photographic drawing.

What I claim as new and of my invention or production and desire to secure by Letters Patent, is the above described configuration of, and arrangement of ornaments and mouldings upon, the end and side plates of the elevated ovens of Baking stoves.
